MEANS FOR COVERING CARGO HATCHES
AND OTHER OPENINGSHenry E. Frick, Upper Montclair, N. J., assignor
to The Metal Lumber Corporation of New Jersey, New York, N. Y.

Application July 18, 1936, Serial No. 91,287

6 Claims. (Cl. 114—201)

This invention relates to cargo hatches for vessels and has for its principal object the provision of means for covering the same or similar openings, said means comprising a plurality of units, 5 each unit consisting of a casing made up of a sheet of thin steel and preferably filled with fire-retardant material.

A further object is the production of a reinforced metal plank filled with fire retardant material and adapted to be used singly or with other 10 planks in closing various shaped apertures.

Another object is the production of a metal plank the casing of which is made of thin metal and provided with U-shaped reinforcing partitions or flanges extending the entire length of the plank, the abutting parallel portions of said partitions or flanges being either spot welded or continuously welded together.

The present invention is an improvement on 20 the invention covered by Patent No. 1,777,880, issued October 7, 1930, to Eric H. Ewertz and John T. Dalcher.

The above and other desired objects are attained by the mechanism illustrated in the accompanying drawing.

For the purpose of illustrating the invention, one preferred form thereof is illustrated in the drawing, this form having been found to give satisfactory and reliable results, although it is 30 understood that the various instrumentalities of which the invention consists can be variously arranged and organized, and the invention is not limited to the precise arrangement and organization of these instrumentalities as herein shown 35 and described except as required by the scope of the appended claims.

Of the drawing—

Figure 1 represents a vertical section of a cargo hatch showing a plurality of metal planks or units 40 covering the same.

Figure 2 represents a plan of one of said planks or units.

Figure 3 represents a transverse section of the same drawn to an enlarged scale, the cutting 45 plane being on line 8, 8 on Fig. 2, said unit being formed of one continuous sheet of metal and open at the bottom.

Figure 4 represents a similar transverse section of a modified form of unit formed from a single 50 sheet of metal and filled with a fire retardant material.

Figure 5 represents a similar transverse section showing a unit made up of top and bottom sheets of material and filled with fire retardant material, this particular unit being provided with a

groove on one side face and a tongue on its opposite side face.

Figure 6 represents a similar transverse section of a unit made up of top and bottom sheets of metal and filled with fire retardant material. 5

Figure 7 represents a longitudinal section of one of the planks or units, the section being on line 7, 7 on Fig. 3.

Figure 8 represents a section on line 8, 8 on Fig. 3 and

Figure 9 represents a diagram showing a plurality of planks or units disposed side by side in position to cover a cargo hatch or other opening.

Similar characters indicate like parts throughout the several figures of the drawing.

In the drawing, 10 is a deck of a vessel having secured thereto a hatch frame 11 by means of angle irons 12 and bracing members 13.

Depending from the hatch frame 11 and secured to the deck 10 by angle irons 14 is a supplemental hatch frame 15. 20

Extending transversely of the hatch frame 11 are a plurality of removable hatch beams or strongbacks 16 and 17, the strongback 17 having flanges 18 extending upwardly above the top of 25 the hatch beams 16, as shown in Fig. 1 of the drawing.

Secured to the inner face of the hatch frame 11 and at the upper end thereof are angle irons 19, the inwardly extending flanges of which are 30 aligned with the upper flanges of the hatch beams 16 and 17. The hatch frame forms no part of the present invention and may be made of any well known construction.

On the upper flanges of the hatch beams 16 and 35 17 and inwardly extending flanges of the angle irons 19 are disposed a plurality of cover units 20.

These cover units 20 may be of any desired length to accommodate them to various conditions, as for instance, as shown in Fig. 1 two 40 long units are shown at the left of said figure and a shorter unit at the right thereof.

When the units 20 have been removed, the hatch beams 16 and 17 may also be removed to give a clear hatch opening. 45

These units 20 may be made up in different ways, either from one sheet of thin steel or from two sheets of steel welded together at their adjoining edges.

As shown in Fig. 3 a unit is made up of a single 50 sheet 21 of thin steel in the form of a box, the lower end thereof having flanges 22 extending toward each other and welded to a brace or strap 23 superimposed on said flanges.

One or more of these straps 23 may be used 55

according to the length of the unit and where several straps 23 are used they are spaced, as shown in Fig. 7 of the drawing, about thirty inches apart, more or less to suit varying conditions.

5 Near either end of each unit 20 is a cup-shaped depression 24 formed in the sheet metal top, said depression having welded to its upper face a cross handle bar 25 with its under face rounded, as indicated at 26 to provide a good grip when positioning the units 20 on the hatch 11 or removing the units therefrom. The top of handle bar 25 is flush with the top surface of the unit 20.

10 On opposite sides of the depressions 24 and 15 extending the entire length of each plank or unit 20 are U-shaped strengthening flanges or ribs 27, the lower ends of which are welded at 28 to the strap 23.

15 The two abutting parallel portions of the 20 flanges 27 are continuously welded together, thereby increasing the rigidity of said flanges.

20 To the inner surfaces of the side walls of the 25 plank or unit 20 shown in Fig. 3 and to the outer faces of the U-shaped flanges or ribs 27 are tack-welded a plurality of angle irons or 25 clips 29 supporting a plate 30 of pressed asbestos board or some similar fire retardant material against the inner face of the upper wall of said box 21.

30 In some cases this plate 30 may be omitted, if 35 desired, depending upon how the plank or unit is to be used.

It is preferred, however, to have the planks 35 or units 20 in the form of a closed casing with its interior filled with fire retardant material 31, as indicated in Figs. 4, 5 and 6.

40 In Fig. 4 a unit is shown in which a closed casing is formed of one continuous sheet of thin metal 32, the adjoining ends of which are continuously welded together at 33.

45 This form of unit is provided with a depression 24 in the sheet metal 32 and handle 25 welded thereto similar to that shown in Fig. 3 of the drawing and hereinbefore described.

The same depression 24 and handle 25 is used 50 in the plank or unit shown in Fig. 5.

In Fig. 4 the sheet metal 32 is provided with 55 U-shaped partitions 34 on opposite sides of the depressions 24, the two abutting parallel thicknesses of material forming these partitions 34 being spot welded together and giving great 60 rigidity to the casing.

A unit may be formed of two sections of thin 55 sheet metal as shown in Fig. 5, the upper section 35 having formed in one of its side walls a groove 36 and in the opposite side wall a tongue 37 adapted to fit into a groove 36 in an adjacent unit 20. This unit may also be made of one continuous sheet of material with the ends continuously 60 welded together as at 33 in Fig. 4.

The lower section 38 is provided with the two 65 upwardly extending U-shaped partitions or ribs 39, the two abutting parallel portions of the same being either spot welded or continuously welded together to obtain great rigidity for the entire casing of said unit.

The upper section 35 and the lower section 38 are continuously welded together as indicated at 70 40 and 41.

In Fig. 6 the unit is made up of a box portion 42 having a cover portion 43, the downwardly extending flanges 44 being continuously welded at 45 to the side walls of the box portion 42.

75 Embedded in the fire retardant material 31

with which said box 42 is filled is a cup-shaped member 46, one at either end of the unit 20.

5 Across this cup-shaped member 46 is a handle 47, the under side of which is rounded and the upper face of which is flat.

The flat opposite ends of said handle are continuously welded to the under face of the cover portion 43 as indicated in Fig. 6 of the drawing, with a portion thereof flush with the upper surface of the hatch plank.

10 When the planks or units 20 are formed as indicated in Figs. 3, 4, 5 and 6 in section, the opposite ends are closed by plates 48 continuously welded to the opposite ends of the metal casing thereof.

15 If desired, a plurality of said planks or units 20 may be disposed parallel to each other as shown in Fig. 9, to form a complete covering for a hatch, a pit, a tank, or similar device.

The fire-retardant material 31 with which the 20 planks or units 20 are usually filled is generally of a mineral wool type or an asbestos mixture.

Sometimes the hatch opening 11 communicates with a refrigerating space and then the planks 25 may be filled with granulated cork or other insulating material.

The handles 25, 47 may be grasped by a man's hand or with a hand cargo hook.

When the planks or units 20 are provided with 30 tongues 37 and grooves 36, they may be laid on the hatch strongbacks and interlocked, thus firmly securing the covering to the hatch opening.

35 It is self-evident that the hatch covers may be made up of any number of planks or units 20, which planks may be of various widths and 35 lengths to accommodate them to various sizes of openings to be covered.

These planks or units 20 while made of steel are comparatively light owing to the thinness of the steel, but when reinforced with the end plates 40 48 and the longitudinal stiffening U-shaped ribs or partitions 27, 34, or 39, are very rigid, and combining as they do light weight and strength, they are very superior to the wooden covers now in general use, and are so manufactured as to be 45 interchangeable with them without changes in the hatch combings or strongbacks.

Being filled with fire-retardant material the 50 covers when constructed as shown and described are absolutely fireproof.

The invention is not limited to the various forms of covers shown in the drawing for it is perfectly obvious that a great variety of similar designs may be produced.

By making the planks of a continuous sheet 55 of thin metal the depressions 24 for the handle may be formed therein and the handle 25 welded into this depression in a transverse position, as shown in the drawing.

When the two abutting parallel portions of the 60 stiffening ribs or partitions 27, 34 and 39 are are spot welded together, the spots being in staggered relation, considerable rigidity is given to the plank. In some cases the welding may be continuous depending on the condition to be 65 met.

In the form shown in Fig. 4 a single continuous sheet of metal may be used bent to the required form and with the adjoining ends continuously welded together, as shown at 33 in Fig. 4, or two 70 sections of material may be used as shown in Fig. 5, the upper section being formed with the handle depression and with or without the tongue 37 and groove 36 and the lower section being formed with the U-shaped partitions or ribs 39, 75

the two abutting parallel portions of which are spot welded together, or if desired, continuously welded together.

Other variations may be made in the construction of the plank without varying the scope of the present invention but in all cases it is preferred to have strengthening partitions extending longitudinally of the plank on opposite sides of the handle depressions, these partitions being formed of portions of the sheet metal casing folded U-shaped with the two abutting parallel portions thereof welded together.

The strengthening partitions above referred to extending the entire length of each plank divide the said plank into a plurality of compartments, each of which is adapted to be filled with a fire retardant material.

When planks such as shown in Fig. 5 are used to form a cover for a hatch opening and the tongues 37 of the various planks are inserted into grooves 36 in abutting planks, it is quite obvious that the completed cover made up of these several planks thus interlocked will be given great additional rigidity.

When planks of either construction shown in the drawing are used to form a cover for a cargo hatch, there is provided protection against the spread of fire and furthermore the danger of the planks being washed away in a heavy sea is obviated as these metal planks will not float. With wooden covers this washing overboard often occurs but with the metal planks this objection is overcome.

Owing to the smooth surface of the hatch covers, the life of the canvas tarpaulins or other hatch coverings is greatly prolonged.

The metal planks herein shown and described are made interchangeable with the present type of wooden hatch planks in general use and these metal planks may be substituted for the wooden planks without making any changes in the hatch combings which are installed on the vessel.

As a consequence these metal planks may be installed on vessels already in service or they may be made to adapt them for any new construction of vessel.

These planks being filled with fire retardant material serve as fire stops and prevent the spread of fire to other compartments of the vessels.

The planks may be manufactured in either one piece of metal or of two pieces of metal as any particular requirement may warrant.

It will also be understood that the various jointures of the metal casing may be either spot welded or continuously welded as particular cases may require.

It is obvious that the use of this plank insures

a greater degree of safety against fire than can be obtained where wooden planks are used.

The planks are easy to handle and may be manufactured readily with comparatively little expense.

These planks have already been approved by Lloyd's Register of Shipping and the American Bureau of Shipping for use on such vessels as come under their classification.

It is believed that the many advantages of the invention will be understood readily without further description.

Having thus described my invention, I claim:

1. A plank for covering hatches and other openings consisting of an elongated casing formed of two thin metal sheets constituting two sections, a portion of one of which is inserted within the other, said casing having between and parallel with its narrower longitudinal sides U-shaped reinforcing partitions formed of one of said thin metal sheets and having abutting portions welded together, and continuous weld means uniting overlapping portions of said sections together thereby forming an enclosed casing.

2. A plank as set forth in claim 1 having depressions in its top section, and a half oval bar fitted to each depression and welded at opposite ends to the wall of said depression with its upper face flat and flush with the top of said plank.

3. A plank as set forth in claim 1 having longitudinal compartments formed by said reinforcing partitions and the walls of the casing, which compartments are filled with fire retarding material.

4. A plank as set forth in claim 1 having at opposite ends closing plates welded to the ends of said casing and said partitions.

5. A plank as set forth in claim 1 in which the narrower longitudinal sides have aligned flat portions extending lengthwise thereof and between which one side has a V-shaped projection and the opposite side has a corresponding V-shaped depression.

6. A plank for covering hatches and other openings consisting of an elongated casing closed at both ends and formed of thin metal with upper and lower walls and narrower longitudinal sides, one of said walls having formed thereof U-shaped reinforcing partitions extending to the other wall and having abutting portions welded together, said partitions being between, parallel with and separated from said narrower longitudinal sides, and continuous weld means uniting overlapping portions of said thin metal thereby forming an enclosed casing.

HENRY E. FRICK.
